UNITED STATES PATENT OFFICE.

ABNER F. H. DAVIS, OF OAKLAND, CALIFORNIA.

ELECTRIC SWITCH.

1,315,182.

Specification of Letters Patent. Patented Sept. 2, 1919.

Application filed August 22, 1916. Serial No. 116,403.

To all whom it may concern:

Be it known that ABNER F. H. DAVIS, a citizen of the United States, and residing at Oakland, in the county of Alameda and 5 State of California, has invented certain new and useful Improvements in Electric Switches, of which the following is a specification.

This invention relates to improvements 10 for preventing the theft of automobiles and has as its principal object the construction of an improved system by which the circuit to the spark plugs may be interrupted and in order to reestablish the circuit it is necessary to set a number of dials to a given combination.

Still another object of my invention is to provide switch means by which the combination may be readily changed and in general to provide a system which will absolutely prevent the establishment of a circuit to the spark plugs without a knowledge of the proper setting of the various switch members.

25 With these and other objects in view, the invention consists in the novel construction, combination and arrangements of parts herein illustrated and more specifically pointed out in the appended claims.

30 Referring to the drawings forming a part of this specification:

Figure 1 is a view of front elevation of a switch plate showing an arrangement of dials thereon for controlling the circuits of 35 a 4-cylinder engine,

Fig. 2 is a view in rear elevation of same,

Fig. 3 is a view in rear elevation of one of the switch members,

Fig. 4 is a view in section through this 40 switch member,

Fig. 5 is a diagrammatic view showing the manner in which the improved switch is connected between the source of electrical energy and the various spark plugs.

45 Referring to corresponding parts of the several views by the same numerals of reference, 1 denotes the switch plate on the back of which is mounted various switch members 2. These members may be of any

50 preferred construction but as here illustrated consist of the disks of insulation 3 and 4 between which is held a metallic disk 5. These various disks are held together by means of screws 6 and they are provided

55 with the alining openings 7, which openings

have screw threads through the disks 4 and 5. The contact studs are denoted by 8 and 9; the former being the contact member by which a circuit is completed through the switch, while the latter is a blank contact. 60 The contacts 8 are provided with the screw portions 10 which extend through disk 4 and engage the threads of plate 5, while the contacts 9 are provided with screws 11 which only engage the insulating disk 4. By this 65 construction when it is desired to change the combination of the device it is only necessary to remove the screw 8 and one of the short screws 9 and interchange their position. This construction also prevents 70 the combination being read by an inspection of the rear of the switch. The switch members 2 are attached to the rear of plate 1 in any preferred manner and the whole contained in a suitable box or case to prevent 75 access to the rear.

Through the center of each switch member extends a shaft 12 which also extends through openings in plate 1 and is provided on the outside with an indicating arm 13 80 and a button 14 by which it may be turned. On the other side of the switch it is provided with a contact arm 15 held between a spring washer 16 and fastening means, such as a nut 17. Surrounding the shaft is a ring 18 85 having a radially extending arm 19, on the outer end of which is a screw 20 serving as a binding post. The plate 5 has a laterally extending ear 20' in which is a screw 21 serving as the binding post for the opposite terminal.

In the preferred embodiment of my system, I provide a switch member for each cylinder and two switch members which are interposed between the source of electrical 95 energy and the timer. In the diagrammatic view, 22 denotes the magneto, 23 a set of batteries, both of which are grounded and indicated at 24. Conductors 25 and 26 extend to the terminals of the 2-way switch 100 27 and these conductors may be provided with suitable fuses 28. From the main terminal of the 2-way switch a conductor 29 extends to the contact 8 of the first switch member from the opposite terminal of which 105 the conductor 30 extends to one terminal of a second switch member, and from the opposite terminal of the latter a conductor 31 extends to the timer 32. From the timer conductors 33 extend to one terminal of the 110

same number of switch members, and from the opposite terminals of each of these switch members conductors 34 extend to the various spark plugs 35, which as usual are grounded, as indicated at 36.

The front of plate 1 is provided with indicating characters 40, either numerals or letters, which are positioned in the same angular relation as the contact studs on the switch members 2; thus, as illustrated in Fig. 1, reading across the top, then across the bottom row from left to right, the combination is, 1, 2, 8, 3, 4, 8. The arms in Fig. 5 being shown diagrammatically in the same position. Thus the current from the magneto flows through conductor 25, switch 27, conductor 29 to the first switch 2. Here it flows through the screw 8, the plate 5, shaft 12, member 19 of that switch to conductor 30. The circuit continues through this conductor to the next switch, flowing through it in like manner and thence to the timer 32; from this timer current flows through the various other switches, 2 corresponding in number to the cylinders of the engine and from each of these switches a conductor 34 leads to the spark plugs. Thus if the switch arms 15 of the switches to which the conductors 29 and 30 are not positioned on their respective contacts 8, a circuit is not completed to the timer. Even should the circuit be completed through these two switch members it would be further necessary to complete the circuit through two or more remaining switches in order to obtain sufficient power to run the engine.

While I have illustrated switch members with eight points of contact, it will be understood that a larger number may be used, thus greatly increasing the number of possible combinations. I have in this manner provided a simple and effective means of preventing the unauthorized starting of an automobile engine and consequent theft of the car. My device has no parts to become lost as in the various devices requiring a padlock, neither has it a key which is liable to suffer the same fate.

While I have shown the preferred construction and embodiment of my invention, let it be understood that I do not wish to

limit myself to the construction shown in so far as the limit is implied to the scope of the claims.

55

I claim as new and wish to cover by Letters Patent:

1. An electrical switch comprising a dial plate, a plurality of switch members, each member comprising a contact arm, a plurality of removable studs, a conducting disk, an insulating disk, one only of said studs engaging said conducting disk, a conducting arm in electrical connection with said contact arm and binding screws on said conducting disk and said conducting arm.

2. An electrical switch comprising a dial plate, a switch member, a plurality of contact studs mounted in said switch member, a switch shaft, a contact arm on said shaft for wiping said studs, an indicating arm on said shaft in front of said dial plate, an operating button on said shaft, a conducting plate in said switch member, any one of said studs being interchangeable with any other 75 of said studs and but one of said studs being engageable with said conducting plate.

3. An electrical switch comprising a dial, a switch member, a shaft, an indicating arm on said shaft extending over said dial, a conducting plate in said switch member, a plurality of contacts mounted on said switch member, a switch arm on said shaft adapted to wipe said contacts, any one of said contacts being interchangeable with any other 85 of said contacts and but one of said studs being engageable with said plate.

4. An electrical switch comprising a dial, two insulation disks and a conducting disk arranged between said insulation disks, a shaft extending through said disks, an indicator on said shaft over said dial, the insulating outer disk and the conducting disk being provided with screw holes arranged around said shaft, screw contacts screwing 95 into all except one of the screw holes of said outer insulating disk, a screw contact screwing into the remaining screw hole of said outer disk and one of the screw holes of said conductor disk, and a wiper on said 100 shaft adapted to wipe said contacts.

In testimony whereof I affix my signature.

ABNER F. H. DAVIS.
